UNITED STATES PATENT OFFICE

2,258,767

ELECTROSTATIC SEPARATING APPARATUS

Herbert B. Johnson, Rochester, N. Y., assignor to
 Ritter Products Corporation, Rochester, N. Y.,
 a corporation of New York

Application September 1, 1939, Serial No. 292,980

3 Claims. (CL 209—127)

My invention relates, generally, to electrostatic separating apparatus and it has particular relation to improvements in the electrode construction thereof.

In my Patent No. 2,135,716, issued November 8, 1938, I have shown a plurality of pairs of separating electrodes which are connected across a source of high direct voltage as a result of which a high potential electrostatic field is maintained between each of the pairs of electrodes. The electrodes are generally cylindrical in shape and both of them are rotatable. The material to be separated falls onto one of them, called the material conveying electrode, and it is carried thereby into the electrostatic field where the separating action takes place. It is highly desirable that the high potential electrode have a smooth surface at all times in order to prevent the piling up of particles thereon thereby forming discharge points and causing arcing to take place between the electrodes. In my patent I have provided a wiper that is stationarily mounted with respect to the high potential electrode and engages its surface as it rotates for the purpose of polishing it and removing therefrom any particles which might tend to form discharge points. While this construction is generally satisfactory, I have found that it is likely to result in the wearing of grooves in the high potential electrode due to the lodging of relatively hard particles in the wiper in such manner as to serve as cutting edges. This is undesirable since it results in a roughened surface on the high potential electrode and the formation of sharp corners or points from which arcing may take place.

Accordingly, it is to the solution of this problem that my present invention is addressed.

The object of my invention, generally stated, is to provide for causing relative longitudinal movement between a rotatable cylindrical electrode of a pair of separating electrodes and a wiper associated therewith.

Another object of my invention is to provide for causing longitudinal movement of the wiper relative to the associated electrode.

Still another object of my invention is to cause longitudinal movement of an electrode relative to a wiper stationarily mounted with respect thereto.

Still another object of my invention is to provide for translating the relative movement of an electrode into relative longitudinal movement of a wiper associated therewith.

A further object of my invention is to provide for repeatedly jarring one of the electrodes in

order to cause particles thereon to more readily fall off.

Other objects of my invention will, in part, be obvious and in part appear hereinafter.

5 My invention, accordingly, is disclosed in the embodiments thereof shown in the accompanying drawings, and it comprises the features of construction, combination of elements and arrangement of parts which will be exemplified in the 10 constructions hereinafter set forth, and the scope of the application of which will be indicated in the appended claims.

For a more complete understanding of the nature and scope of my invention, reference may 15 be had to the following detailed description taken in connection with the accompanying drawing, in which:

Figure 1 is a view, in front elevation, of a high potential electrode and wiper therefor arranged 20 to be oscillated with respect thereto;

Figure 2 is a detail sectional view, taken along the line 2—2 of Figure 1, showing, in addition, the material conveying electrode;

Figure 3 shows a modification of the construction 25 illustrated in Figure 1; and

Figure 4 shows still another modification of the construction illustrated in Figure 1.

Referring now particularly to Figures 1 and 2 of the drawing, it will be observed that the reference character 10 designates a high potential electrode that is generally cylindrical in shape and may be of any desired length. The electrode 10 forms one of a pair of electrodes, the other electrode 11 being a material conveying electrode

35 onto which the particles of material to be separated fall and by means of which they are conveyed into the electrostatic field that is maintained between electrodes 10 and 11 under normal operating conditions by connection to a suitable source of high voltage direct current. An angle 12 is provided for guiding the material to be separated onto the material conveying electrode 11. It will be understood that the space between the electrode 11 and the angle 12 becomes filled with the material to be separated and that additional material falling thereon is readily conveyed by the electrode 11 into the electrostatic field as shown.

With a view to insulating the high potential electrode 10, insulators 13 are provided at its ends. They are formed of suitable insulating material such as porcelain or a phenolic condensation product. Short shafts 14 and 15 project from the ends of the insulators 13, as shown, and they are mounted in suitable bearings 16 and

17 that are carried by uprights 18 and 19, respectively. Any suitable means may be provided for rotating the high potential electrode 10. For example, a gear wheel 20 may be provided on the shaft 15, as shown, and it may be driven through suitable driving means as will be readily understood.

The material conveying electrode 11 is arranged to be rotated in the direction indicated by the arrow 21. The high potential electrode 10 may be rotated in either direction depending upon the operating conditions.

As set forth in my patent, referred to hereinbefore, it is desirable to maintain the surface of the high potential electrode 10 in a polished condition in order to prevent the building up of discharge points thereon as a result of the collection of particles on the surface of the material being separated. For this purpose a wiper 24 is provided which extends substantially the entire length of the high potential electrode 10 and covers about one quarter of its circumference. The wiper 24 may be formed of felt impregnated with a suitable abrasive material such as finely ground "Carborundum," rouge, crocus, aluminum oxide or other polishing powder. The wiper 24 is held in proper position by means of a support member 25 in the form of a metal strip to which the wiper may be cemented. Ears 26 are provided at the ends of the support member 25 and they are attached, as shown, to the ends of insulators 27 which are similar to the insulators 13. The insulators 27 are mounted on short shafts 28 and 29 which are arranged for endwise movement in bearings 30 and 31, respectively, that are suitably mounted on the uprights 18 and 19.

As previously indicated, it is desirable to provide for relative longitudinal movement between the high potential electrode 10 and the wiper 24 in order to prevent pitting of the surface of the electrode. For this purpose collars 34 and 35 are provided at the ends of the insulators 13 with sinuous grooves 36 and 37 therein, as illustrated. Cooperating with these grooves 36 and 37 are pins 38 and 39 which extend from end members 40 and 41, respectively, of the insulators 27. If desired, the pins 38 and 39 may be provided with antifriction rollers in order to reduce the friction with the sides of the grooves 36 and 37.

It will now be apparent that rotation of the electrode 10 relative to the wiper 24 causes, in addition, relative longitudinal movement between it and the wiper 24 because of the endwise movement thereof in the bearings 30 and 31 as the pins 38 and 39 follow the grooves 36 and 37. In this wise the surface of the electrode 10 is maintained smooth and polished and there is no likelihood of the formation of grooves therein as a result of the presence of hard particles in the wiper 24.

The material conveying electrode 11 may also be provided with a wiper 42 which is formed of material that is similar to the material of which the wiper 24 is formed and impregnated as described. The wiper 42 may be held in place by any suitable means on the angle 12 such as by bolts 43, as shown.

In Figure 3 of the drawing there is shown another embodiment of my invention. As in the construction as shown in Figure 1 of the drawing, the high potential electrode 10 is arranged for rotary motion only while the wiper 24 and its support member 25 are mount-

ed for endwise movement in the bearings 30 and 31. The support member 25 and associated parts are biased to the right as viewed in the drawing by a compression spring 45 which reacts against a suitable reaction member 46 that may be carried by the upright 18. In order to move the support 25 and the wiper 24 carried thereby longitudinally of the electrode 10, a cam 47 is mounted on a shaft 48 and is arranged to engage the right hand end of the short shaft 28, as shown. The cam 47 may be rotated by any suitable means such as through a gear 49 mounted on the shaft 48 and driven from any suitable driving means.

15 It will be apparent that the rotation of the cam 47 will cause endwise movement of the support 25 and the wiper 24 carried thereby relative to the electrode 10 in one direction and that movement in the opposite direction will be effected by the spring 45. This relative longitudinal movement will take place while the electrode 10 is being rotated as described. The desired polishing action of the surface of the electrode will then be effected because of the combined rotary and translatory movement of it with respect to the wiper 24.

20 In Figure 4 of the drawing there is shown another embodiment of my invention. In this embodiment the electrode 10 is mounted for endwise movement relative to bearings 16' and 17', while the wiper 24 and the support 25 therefore are arranged to be relatively stationary. Instead of moving the wiper 24 along the surface of the electrode, the electrode is moved along the wiper 24.

25 As shown, the electrode 10 is biased to the right, as viewed in the drawing, by a compression spring 51 that is mounted within a suitable tubular housing 52 carried by the upright 18. An adjustable plug 53 is threaded into the end of the tubular housing 51 and its position can be changed in order to vary the biasing force of the spring 51.

30 In order to effect endwise movement of the electrode 10 in the opposite direction, the ratchet wheel 54 is mounted on the shaft 15 and it is arranged to engage a tooth or pawl 55 that may be carried by any suitable support, such as the support member 56 that is mounted on the upright 19. As the electrode 10 is rotated through the gear 20, it will be moved endwise to the left as the teeth of the ratchet wheel 54 ride over the tooth or pawl 55. The spring 51 will return the electrode 10 to the right as each tooth of the ratchet wheel 54 is passed.

35 Because the electrode 10 is moved to the right sharply by the spring 51 as soon as each tooth of the ratchet wheel 54 is passed, a certain amount of jarring action takes place which tends to shake off particles that might otherwise tend to cling to the surface of the electrode 10. This action, in addition to the relative rotary and translatory movement between the wiper 24 and the electrode 10 serves to keep the surface of the electrode free from any of the particles of the material being separated and at the same time prevents the formation of ridges or grooves in the electrode surface.

40 Obviously the positions of the ratchet wheel 54 and of the tooth or pawl 55 could be reversed without departing from the scope of this invention. Since further changes may also be made in the above constructions and different embodiments of the invention may be made without departing from its scope, it is intended that all

matters contained in the foregoing description or shown in the accompanying drawing shall be interpreted as illustrative and not in a limiting sense.

I claim as my invention:

1. In an electrostatic separator for separating a product comprising mixed particles, in combination, a rotatable cylindrical electrode, wiper means containing abrasive material cooperating with said electrode for polishing the same and extending substantially the entire length thereof, and pin and cam means operatively interconnecting said electrode and said wiper means whereby rotation of the former causes slight relative longitudinal movement between said electrode and wiper means.

2. In an electrostatic separator for separating a product comprising mixed particles, in combination, a rotatable cylindrical electrode, wiper means containing abrasive material cooperating with said electrode for polishing the same and extending substantially the entire length thereof,

insulator means mounting said electrode and wiper means for relative longitudinal movement, and pin and cam means operatively interconnecting said insulator means remote from said

5 electrode and wiper means whereby rotation of the former causes slight relative longitudinal movement between said electrode and wiper means.

3. In an electrostatic separator for separating 10 a product comprising mixed particles, in combination, a rotatable cylindrical electrode having rotatable therewith a sinuous groove, wiper means containing abrasive material extending substantially the entire length of said electrode and engaging the same and movable longitudinally thereof for polishing the same, and a pin carried by said wiper means and extending into said sinuous groove whereby the rotary movement of said electrode is translated into longitudinal movement of said wiper means.

HERBERT B. JOHNSON.
